(57) **CLAIM**

I claim the ornamental design of the motorcycle mirror, as shown and described herein.

DESCRIPTION

FIG. 1 shows a back perspective view of a motorcycle mirror, according to the present invention;

FIG. 2 shows a front perspective view of a motorcycle mirror shown in FIG. 1, according to the present invention;

FIG. 3 shows a back view of the motorcycle mirror shown in FIG. 1;

FIG. 4 shows a front view of the motorcycle mirror shown in FIG. 2;

FIG. 5 shows a right side view of the motorcycle mirror shown in FIG. 3;

FIG. 6 shows a left side view of the motorcycle mirror shown in FIG. 3;

FIG. 7 shows a top view of the motorcycle mirror shown in FIG. 3; and,

FIG. 8 shows a bottom view of the motorcycle mirror shown in FIG. 3.
